Primary Examiner — Jennifer L Rempfer*Assistant Examiner* — Aaron C Fowler(74) *Attorney, Agent, or Firm* — Wood Herron & Evans LLP(57) **CLAIM**

The ornamental design for a wheel, as shown and described.

DESCRIPTION

FIG. 1 is a front right perspective view of a wheel according to the present invention.

FIG. 2 is a front view of the wheel shown in FIG. 1; and, FIG. 3 is a left side view thereof, the right side view being a mirror image thereof.

The broken lines form no part of the claimed design, but instead show environmental structure.

1 Claim, 3 Drawing Sheets(56)
